(57) **CLAIM**

The ornamental design for a firearm trigger chock as shown and described.

DESCRIPTION

FIG. 1 is a front perspective view of a first embodiment of a firearm trigger chock showing the new design;

FIG. 2 is a rear elevation view thereof;

FIG. 3 is a front elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a rear-side perspective view thereof;

FIG. 9 is a front perspective view of a second embodiment of a firearm trigger chock showing the new design;

FIG. 10 is a rear elevation view thereof;

FIG. 11 is a front elevation view thereof;

FIG. 12 is a right-side elevation view thereof;

FIG. 13 is a left-side elevation view thereof;

FIG. 14 is a top plan view thereof;

FIG. 15 is a bottom plan view thereof;

FIG. 16 is a rear-side perspective view thereof; and,

FIG. 17 is an elevation front view of the second embodiment of the firearm trigger chock shown with an environmental firearm.

The broken lines in the drawings are for the purposes of illustrating environmental subject matter that forms no part of the claimed design.
